UNITED STATES PATENT OFFICE

GEORGE L. HINMAN, OF NEW HAVEN, CONNECTICUT, ASSIGNOR TO THE GREIST MANUFACTURING CO., OF NEW HAVEN, CONNECTICUT, A CORPORATION

DOORLATCH

Application filed December 15, 1927. Serial No. 240,181.

My invention relates to an improved door latch of the type having an inside and an outside handle in which the retraction of the latch-bolt by the outside handle may be at any time forestalled by a supplemental movement of the inside handle in the reverse direction from that required for retracting the latch-bolt thereby, the object being to produce, at a low cost for manufacture, such a latch constructed with particular reference to simplicity, fewness of parts, ruggedness, reliability, and convenience of use. My improved latch, while designed with particular reference for use on the doors of automobiles, is not so limited.

With these ends in view, my invention consists in a door latch characterized by having a reciprocating latch-bolt, inside and outside handles, inside and outside roll-backs respectively connected with the said handles, and a blocking-finger carried by the inside roll-back and movable by a supplementary reverse movement of the inside handle into the path of movement of the outside roll-back for preventing the retraction of the bolt by the said outside handle.

My invention further consists in a latch-bolt characterized as above and having certain details of construction and combinations of parts as will be hereinafter described and particularly pointed out in the claims.

In the accompanying drawings:

Fig. 1 is a top edge view of a remote control latch-bolt mechanism embodying my invention;

Fig. 2 is a view thereof in elevation, looking from the outside of the door;

Fig. 3 is a detached perspective view of the inside roll-back thereof;

Fig. 4 is a corresponding view of the outside roll-back;

Fig. 5 is a top edge view of a self-contained form of latch-bolt which my invention may assume, in this form the outside handle being installed in the same frame-plate as the inside handle;

Fig. 6 is a view in elevation, looking from

the outside of the door with the retaining-plate or cover removed; and

Fig. 7 is a detached perspective view of the inside roll-back thereof.

In carrying out my invention, as shown in Figs. 1 to 4 inclusive, it is embodied in a latch-bolt of the so-called "remote-control" type, by which is meant a latch-structure in which the inside handle is located at a considerable distance from the edge of the door in which the latch-bolt itself is installed, for greater convenience in operating the latch from the inside of a car. This latch in question is provided with an inside lever-handle 10 and an outside lever-handle 11, either one of which is adapted to effect the retraction of a heavy sheet-metal latch-bolt 12 having a beveled nose 13 secured to it by rivets 14. The said nose 13 projects through an opening 15 in a flange 16 turned outward at a right angle from a rectangular frame-plate 17. The inner end of the latch-bolt 12 is guided by a roller 18 turning on a stud 19 projecting outwardly from the said frame-plate 17, the bolt being provided with a clearance-slot 20 into which the roller 18 projects and upon the walls of which it rides. The bolt is normally retained in its projected position by a spiral spring 21, the outer end of which engages with the heel 22 of the bolt, while its inner end is secured to a post 23 offstanding from the plate 17. The bolt is held in place by means of a retaining-plate 24 secured in spaced relation to the frame-plate 17 by screws 25 and spacing-studs 26.

At its inner end, the bolt is provided with an upstanding-arm 27, the forward face of which is engaged by a cam-surface 28 upon the inner edge of an inside roll-back 29 which is formed with a perforation 30 by which it is mounted upon a stud 31 in the plate 17. The said roll-back is formed with an upstanding-arm 32 pivotally connected by a rivet 33 with the outer end of a long horizontally-arranged link 34, the inner end of which is pivotally connected by a rivet 35 with the upper end of an arm 36 carried by the spindle 37 of the inside lever-handle 10, the said spindle being installed in a

handle mounting-plate 38 provided with screw-holes 39 for fastening it to the inside of a car door. The said plate 38 is furnished with a retaining-plate or cover 40 which holds the upstanding-arm 36 in place upon the spindle 37.

For the retraction of the latch-bolt 12 from the outside of the door, the spindle 41 of the outside handle 11 is entered into the 10 squared opening 42 of an inside roll-back 43, the inner edge of which co-acts for retracting the latch-bolt, with a curved finger 44 upstanding therefrom and integral therewith.

15 It is clear from the foregoing description that the latch-bolt 12 may be retracted against the tension of its spring 21 by a suitable movement of either the outside handle 10 or the inside handle 11.

20 To enable the latch-bolt to be locked when desired against retraction by the outside handle, the inside roll-back 29 is provided with an integral offsetting blocking-finger 45 having a blocking-face 46 co-acting, 25 under predetermined conditions, with a blocking-face 47 formed upon a complementary blocking-finger 48 projecting inwardly from the upper end of the outside roll-back 43.

30 In the ordinary operation of the latch-bolt by its inside or outside handle, the blocking-fingers 45 and 48 turn with their respective roll-backs, with which they are integral, without ever being brought into 35 collision, since, normally, both of the roll-backs are turned inwardly away from the edge of the door. Thus, for the retraction of the bolt from the outside of the door, the handle 11 is swung downwardly, with the 40 effect of turning the roll-back 43 inwardly, away from the edge of the door, against the upstanding bowed arm 44 of the latch-bolt, which is thus retracted; while to effect the retraction of the latch-bolt from the inside 45 of the door, the inside handle 10 is swung rearwardly away from the edge of the door in the direction of the arrow *a* in Fig. 2, whereby the arm 36 carried by the spindle 37 exerts a thrust on the link 34, moving the 50 same outward toward the edge of the door and correspondingly rocking the arm 32 of the inside roll-back 29, the cam-surface 28 of which moves rearward against the up-standing arm 27 of the latch-bolt and re- 55 tracts the same.

The blocking-fingers 45 and 48 are so positioned that, during the two operations above described, they are not brought into collision. However, in case the user of the 60 car desires, on leaving it, to prevent the door from being opened from the outside, he may forestall this by a supplementary reverse movement of the inside handle 10. When this handle is swung outwardly toward the 65 edge of the door in the direction of the ar-

row *b* (Fig. 2) into the position in which it is shown by broken lines in the said figure, the blocking-finger 45 of the inside roll-back is lifted into the path of movement of the blocking-finger 48 of the outside roll-back 43, as also shown in Fig. 2; the stop 49 on the finger 45 checking the upward swing of the latter. The parts now occupy the positions shown by broken lines in Fig. 2. It will be noted, in the said figure, that the 70 said blocking-fingers are engaged above the line *c* drawn between the centers about which the respective roll-backs turn. Now, when an effort is made to turn the outside roll-back by depressing the outside handle, a 80 jam takes place and effectually prevents such turning movement and, therefore, the retraction of the bolt, from the outside of the car, the door of which is thus effectually locked. To restore the latch to what may be 85 termed its status quo, it is only necessary to swing its inside handle 10, as shown by broken lines in Fig. 2, to the position in which it is shown in full lines in the same figure, whereby the blocking-finger 45 of the 90 inside roll-back is moved out of the path of movement of the blocking-finger 48 of the outside roll-back, leaving the latter free to effect the retraction of the bolt.

The inside roll-back 29 is maintained in 95 its normal position, as shown by full lines in Fig. 2, or in its supplementary or blocking position, as shown by broken lines in the same figure, by means of a detent-spring 50 having dwells 51 and 52 for the reception 100 of a nose 53 formed upon the inner edge of the roll-back.

In the self-contained form of my improved door latch shown by Figs. 5, 6 and 7 of the drawings, the several parts are the same as 105 already described, with the exception that the spindle 37 is also mounted in the frame-plate 17, thus dispensing with the secondary plate 38, the arm 36, the link 34, and the arm 32 of the roll-back 29, which latter assumes the form shown in Fig. 7. Both spindles and handles and their related parts are thus organized on the frame-plate, the only substantial difference being that the latch 110 now being described does not provide for what is known as "remote control." The operation of the latch under consideration is the same in every respect as the latch first mentioned.

I claim:

1. A door latch, having a reciprocating latch-bolt; inside and outside handles; inside and outside roll-backs respectively connected with the said handles; and a blocking-finger carried by the inside roll-back 125 and movable by a supplementary reverse movement of the inside handle into the path of movement of the outside roll-back for preventing the retraction of the bolt by the said outside handle.

2. A door latch, having a reciprocating latch-bolt; inside and outside handles; inside and outside roll-backs respectively connected with the said handles; and blocking-fingers carried by the respective roll-backs,
5 the blocking-finger of the inside roll-back being adapted to be brought, by a supplementary reverse movement of the inside handle, into the path of movement of the blocking-finger of the outside roll-back for preventing the retraction of the bolt by the outside handle.
- 10 3. A door latch, having a reciprocating latch-bolt; inside and outside handles; inside and outside roll-backs respectively connected with the said handle; a blocking-finger carried by the inside roll-back and movable by a supplementary reverse movement of the inside handle into the path of
15 movement of the outside roll-back for preventing the retraction of the bolt by the outside handle; and a stop formed upon the blocking-finger of the inside roll-back to engage with the outside roll-back to arrest
20 its movement when it reaches its blocking position.
- 25 In testimony whereof, I have signed this specification.

30
